US0D1002831S

(12) **United States Design Patent** (10) **Patent No.:** **US D1,002,831 S**
(45) **Date of Patent:** **** Oct. 24, 2023**

(54) **ESSENTIAL OIL DIFFUSER**

(71) Applicant: **Jason Ip**, Vancouver (CA)

(72) Inventor: **Jason Ip**, Vancouver (CA)

(**) Term: **15 Years**

(21) Appl. No.: **29/826,666**

(22) Filed: **Feb. 14, 2022**

(51) LOC (14) Cl. **23-04**

(52) U.S. Cl.

USPC **D23/366**
